CLAIM

The ornamental design for a video conference terminal, as shown and described.

DESCRIPTION

FIG. 1 is a front perspective view of a video conference terminal showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof with disclaimed structure removed for clarity purposes;

FIG. 10 is a rear perspective view thereof with disclaimed structure removed for clarity purposes;

FIG. 11 is a front perspective view of the video conference terminal with the bracket in an alternative position; and, FIG. 12 is a rear perspective view of the video conference terminal with the bracket shown in an alternative position. The broken lines depicting the remainder of the video conference terminal form no part of the claimed design.

1 Claim, 12 Drawing Sheets
